UNITED STATES PATENT OFFICE.

HUGO LICHTE, OF KIEL, GERMANY, ASSIGNOR TO SIGNAL GESELLSCHAFT MIT BESCHRÄNKTER HAFTUNG, OF KIEL, GERMANY.

MICROPHONE.

Application filed August 30, 1923, Serial No. 660,114, and in Germany September 7, 1922.

This invention relates to apparatus and arrangements, such as microphones or the like, in which fluctuating currents are produced by variations of the electrical conductivity of a substance or a mixture or composition of substances inserted between electrodes, the said variations of conductivity being caused by alternating mechanical impulses applied to the electrodes. Preferably the invention contemplates arrangements of the kind which are built up as vibratory structures of a definite natural frequency, such as tuned microphones.

A well known drawback in apparatus of this character is the changeability of their natural frequency. It is the object of the invention to diminish or entirely to annihilate this changeability. The invention is based upon the following deliberation: The primary object of my invention is to provide in a vibratory structure for transforming mechanical vibrations into electric current variations, an improved relation between, and arrangement of the masses in different portions of said structure, one of said portions having a constant elastic force and the other of said portions having a variable elastic force. More specifically stated, this improved relation and arrangement contemplates such a preponderance in the size of the portion having a constant elastic force over the size of the portion having a variable elastic force that any variation in the variable elastic force in the latter will not produce in the vibratory structure as a whole a greater variation of elastic force than is permissible under a predetermined limit.

A microphone constructed according to the principles of the present invention is especially adapted for signalling purposes, my invention in such an adaptation making it possible to maintain the natural tuning of the microphone constant as permanently as possible. The function of a microphone constructed in this manner is to be found wherever it is desirable to employ a microphone having a constantly uniform natural tuning.

Mechanical oscillatory structures of this kind comprise masses M and elasticity E upon the amount of which depends their natural frequency. Masses and elasticity are defined by the dimensions of the structural parts of the apparatus. The masses are, as

a rule, invariable, but not the elasticity E because the latter contains a variable and an invariable component. The variable component is represented by the elasticity E_q of the material or substance of variable conductivity.

This fact becomes clear from the example of the granular microphone. The granulated carbon contains the elasticity E_q the amount of which varies with the varying compactness of the granulated carbon. If the component E_q is a substantial part of the total elasticity E of the elastic system vehement variations of the natural frequency of the said system are caused by the variations of E_q .

The invention consists in designing the oscillatory structure represented by the apparatus so that the elasticity of the variable substance, for instance of the granulated carbon within the microphone, is small in comparison with the total elasticity of the system, i. e.

$$E_q \ll E$$

The meaning of this deliberation may be elucidated by the example of an oscillatory microphone of definite natural frequency for a definite maximum current. Cross section and height of the carbon chamber are given by the maximum current. Therefrom results a definite quantity q of granulated carbon the elasticity E_q of which can be found by calculation or by experiment. Besides may be given the desired natural frequency n of the microphone and the allowable difference r of this natural frequency in percents of this frequency.

By experience the usual variations of the elasticity of the carbon contents are known which all may easily be found by experiments under similar conditions as they arise for microphones in normal use.

For the natural frequency of microphone the following equation exists:

$$(1) \quad n = k \sqrt{\frac{E}{M}}$$

in which k is a constant, E the total elasticity, and M the total mass of the oscillatory structure.

E in this equation may be divided into two components E_c and E_q , E_q being the in-

variable part of the elasticity of the system. Then is:

$$5 \quad (2) \quad n = k \sqrt{\frac{E_0}{M} + \frac{E_q}{M}}$$

The allowable difference in the natural frequency may be $\pm rn$. The usual variation of the elasticity of the carbon contents may be found as $\pm pE_q$.

10 Equation (2) thus becomes

$$(3) \quad n \pm rn = k \sqrt{\frac{E_0 + E_q \pm pE_q}{M}}$$

15 from which in connection with Equation (1) the values $\frac{E}{E_q}$ and M may be calculated, which must exist as a minimum for the given frequency n . The approximate values

20 for M and $\frac{E}{E_q}$ are

$$M = \frac{k^2 p E_q}{2 r n^2}$$

25 and

$$\frac{E}{E_q} = \frac{p}{2r}$$

Therefrom the engineer may find out the 30 dimensions of the diaphragm for the microphone and of the mass of the oscillating structural elements, if p , r , n and E_q are given.

35 In the drawing an example of the invention is shown represented by an oscillatory microphone connected to an oscillating diaphragm.

40 A casing with an aperture in the front is closed by an oscillatory diaphragm 1 upon which the microphone is mounted. The microphone consists of two masses 3 and 4 and a diaphragm 2, the mass 3 being shaped as a casing enclosing the chamber for the granulated carbon contents 5.

45 For microphones which are used in connection with other oscillatory structures (diaphragm 1 or the like) and which consist of two masses (3, 4) connected by an elastic member (diaphragm 2) it is usually 50 sufficient to calculate the amount of the so called free mass 4 instead of the total mass. This rule exists especially for microphones of submarine sound receivers where the mass 3 is relatively large compared with the 55 freely oscillating mass 4 because 3 is composed of a relatively large structural mass mounted upon the receiving diaphragm 1, of a relatively large part of this diaphragm itself and of a remarkable volume of water 60 co-oscillating with diaphragm 1.

Sufficient results with regard to the constancy of the natural frequency of such microphones are obtained if the constant component E_0 is at least four times as great as 65 the variable component E_q , with other words,

if E_q is about one fifth of the total elasticity E of the oscillatory structure represented by the microphone.

For the usual currents of 50-100 milli- 70 amperes, i. e. for the usual volume of granulated carbon of such microphones and for the usual frequency of submarine signaling of about 1000 oscillations per second is given a freely vibrating mass of about four grams or more for a loose coupling of the microphone with the receiving diaphragm (a coupling of about 10%).

75 The invention may be applied to microphones and detectors of any kind in which the variable resistance represents at the same time a variable part of the elasticity of the oscillating system.

I claim:

1. A microphone comprising a substantially rigid casing, an elastic diaphragm 85 having a constant elastic force forming one side of said casing, an electrode secured to said casing, a second electrode secured to said diaphragm in proximity and parallel to said first electrode, a filling of granular carbon substance having a variable elasticity included between said electrodes, the elastic force of the said diaphragm being substantially four times the elastic force of said granular filling. 90

2. An apparatus for transforming mechanical vibrations into electric current variations comprising a vibratory structure composed of a rigid member, an elastic member having a constant elastic force, supported by 100 said rigid member, a pair of electrodes, one of said electrodes being mounted on said rigid member, the second electrode being mounted on said elastic member, granular carbon substance having a variable elastic force included between said pair of electrodes, the elastic force of said carbon substance being small compared to the elastic force of said elastic member. 105

3. A submarine sound receiver comprising 110 a watertight casing, a diaphragm, forming part of said casing, a microphone connected to said diaphragm and within said casing comprising a rigid member attached to said diaphragm, an elastic member having a constant elastic force supported by said rigid member, two electrodes mounted between and respectively on said rigid and said elastic members, a granular carbon substance having a variable elastic force included between said electrodes, the elastic force of the said carbon substance being less than one-fourth of the total elastic force of the receiver. 115

4. A microphone of the type described including a vibrating structure possessing a substantially constant elastic force and microphonic material operating in conjunction with said vibrating structure upon the receipt of a signal possessing a varying 120 125

- elastic force, the said constant elastic force being substantially the greater part of the total elastic force of the said microphone, whereby the frequency of said microphone is 5 at all times substantially unchanged.
5. A microphone of the type described, including a vibrating structure possessing a substantially constant elastic force and microphonic material operating in conjunction with said vibrating structure upon the receipt of a signal possessing a varying elastic force, the said constant elastic force being substantially four times the said varying elastic force of the said microphone.
- 10 6. A microphone of the type described including a vibrating structure possessing a substantially constant elastic force and granular carbon filling means compressed by the action of the vibratory structure, the compressional force furnished by the granular carbon filling means being small compared to the elastic force of said vibratory structure.
- 15 7. A microphone of the type described having a diaphragm of relatively large mass, 25 resistance varying means exerting a variable pressure against said diaphragm, the effective mass of said resistance varying means on said diaphragm being small as compared to the mass of said diaphragm.
- 20 8. A microphone of the type described having a diaphragm with a large central mass, resistance varying means exerting a variable pressure against said diaphragm, the effective mass of said resistance varying 35 means on said diaphragm being small as compared to the mass of said diaphragm.
9. A microphone of the type described having a casing of relatively large mass, a diaphragm mounted on said casing having a 40 relatively large central mass and a resistance varying means exerting a variable pressure over only a small area of said diaphragm, the effective mass of said resistance varying means on said diaphragm being small as 45 compared to the mass of said diaphragm.

In testimony whereof I affix my signature.

HUGO LICHTE.
